HYDROFORMING PROCESS

Albert B. Welty, Jr., Westfield, N.J., assignor to Esso Research and Engineering Company, a corporation of Delaware

Application December 28, 1955, Serial No. 555,885

7 Claims. (Cl. 208—65)

The present invention relates to improvements in hydroforming. More particularly, the present invention relates to the hydroforming of the naphtha in the presence of platinum in a fixed bed type of operation in which process the total naphtha is fractionated to obtain a low boiling fraction boiling up to 200° F. and a higher boiling fraction boiling above 200° F. and separately treating the said fractions under conditions which give improved results.

Hydroforming is a process in which a naphtha is treated in the presence of a solid catalytic material and hydrogen at elevated temperatures and pressures with the result that the naphtha is improved in octane quality. The principal reaction during hydroforming is the dehydrogenation of naphthenes present in the feed to the corresponding aromatics. There is also some isomerization of normal paraffins to form isoparaffins as well as isomerization of alkylated cyclopentanes to cyclohexanes and some hydrocracking of the higher boiling paraffins to lower boiling products. As ordinarily carried out, the process results in the net production of hydrogen but in any event there is no net consumption of hydrogen.

It is now a matter of record and commercial practice in this country to hydroform naphthas in order to produce high quality aviation gasoline and motor fuel. The catalyst employed in hydroforming may be in the form of fixed beds or the catalyst, in powdered form, may be employed utilizing the fluidized solid technique. At the present time the catalysts principally in commercial use are platinum carried on alumina, or molybdenum oxide carried on alumina, the former being used in the form of fixed beds in a multi-stage operation with reheating between stages, while the latter is being employed in the form of a fluidized bed.

In hydroforming naphthas the optimum pressure is different for various boiling range naphthas. In general, high boiling naphthas are treated at moderately high pressures for best results. The lower boiling naphthas, on the other hand, and in particular, the naphtha fractions boiling below 200° F. are treated at fairly low pressures for best results.

These phenomena are due to the fact that the high hydrogen partial pressure characteristic of the high pressure operation tends to prevent formation of aromatics from paraffins and dimethylcyclopentanes, which are the principal constituents of all virgin naphthas boiling below 200° F. These naphthas may contain some benzene and cyclohexane, but the quantity present is usually quite small. On the other hand, most naphthas, boiling above 200° F. and say up to 300 or 400° F., are relatively rich in cyclohexane homologues such as methyl cyclohexane, dimethylcyclohexane, etc. All cyclohexane homologues are very readily converted into aromatics by dehydrogenation at normal hydroforming temperatures even at very high pressures, like 400–600 p.s.i.

It is clear from this that higher operating pressure,

2

which results in higher hydrogen partial pressure, can be used on the high boiling feeds than on the low boiling feeds.

The rate of deactivating coke formation on the catalyst determines the length of time it may be used before regeneration is required and also the catalyst life or the length of time the catalyst may be employed before it is required to replace it and, therefore it is desirable to minimize this coke formation. It is common knowledge that the higher the hydrogen partial pressure, the lower the rate of coke formation will be. Therefore, higher pressure operations are required to produce aromatics in good yields with minimum coke formation and longer catalyst life. The optimum operating pressure for high boiling naphthas such as those boiling above 200° F. will be considerably higher than that for low boiling naphthas such as particularly those boiling below about 200° F.

The object of the present invention, therefore, is to hydroform light naphtha and heavy naphtha separately in the same equipment under optimum conditions for each. The present invention provides means whereby this can be accomplished.

In a hydroforming plant designed for hydroforming at say 400 p.s.i.g. if the pressure were to be reduced to say 200 p.s.i.g. during the treatment of the light naphtha, the recycled gas rate (the standard cubic feet of hydrogen containing gas feed to the reaction zone with each barrel of naphtha feed) would be greatly reduced because of the greater pressure drop through the system.

Since one is desirous of reducing hydrogen partial pressure anyway, this greatly reduced recycle gas rate would not be harmful from the standpoint of the reaction itself. However, from the practical standpoint, this is a very serious problem. The hydroforming reaction is highly endothermic, that is, a large amount of heat is consumed when the reaction occurs. The catalyst is disposed in one or more reactors in series and each reactor runs adiabatically, that is, no heat is put into or taken out of each reactor. Because of the large heat absorption by the reaction, there is a large temperature drop from the reactor inlet to outlet. This is undesirable because as the temperature drops, the rate of reaction decreases, and, in fact, this is the reason why it is necessary to use more than one reactor in series and to reheat the hydrocarbon between reactors. The magnitude of this temperature drop is very important in the hydroformer design. If the temperature drop is great, then a large number of reactors and reheat steps are required. This is expensive. If, on the other hand, the temperature drop is very small, only a few reactors with reheat are required.

The temperature drop for a given amount of reaction depends solely on the heat capacity of the vapors flowing through the bed. The higher the heat capacity, the lower the temperature drop will be. For this reason, it is desirable to recirculate as much recycle gas as practical from the standpoint of pressure drop through the system, compressor horsepower required, size of heat exchangers required, etc. With a recycle gas rate, for example, of 6,000 s.c.f./bbl. of feed, the recycle gas actually has more heat-absorbing capacity than the feed itself. In this case, depending somewhat on the nature of the feed stock and severity of reaction, the 6,000 s.c.f./bbl. of recycle gas might have a heat capacity of about 180 B.t.u.'s per ° F. whereas the barrel of feed would have a heat capacity of about 130 B.t.u.'s/° F.

Modifying operating conditions, such as by reducing pressure, so that the recycle gas rate is sharply reduced, the heat absorbing capacity of the vapors passing through

the bed will be much reduced and, therefore, the temperature drop will be very much increased for a given amount of reaction. In practice, what would really happen is that the temperature would get so low that the same amount of reaction could no longer be effected. This means either that the octane number and amount of conversion of the feed will be much reduced or that the naphtha feed rate to the unit must be reduced.

As pointed out previously, however, it is desirable to be able to hydroform both heavy and very light feed stocks in the same unit at conditions approximating the optimum for each. Optimum conditions for the relatively low boiling feed require much lower hydrogen partial pressure than for the higher boiling feed stock. However, when the pressure is reduced in a unit designed for high pressure operation on the high boiling feeds, one can no longer maintain the recycle gas rate necessary to provide the necessary heat-carrying capacity for the vapors as they pass through the bed.

Theoretically, it would be possible to provide additional compressor capacity so as simply to overcome the higher pressure drop caused by the higher velocities when operating at low pressures. Depending on conditions, this might require from two to five times as much compressor capacity and, furthermore, the pressure drop through the catalyst beds would be very high. The high pressure drop through the catalyst beds is undesirable because the catalyst is crushed and reduced in size.

The heat carrying capacity of the recycle gas depends on the gases of which it is composed. On a volumetric basis, hydrogen, which is the principal volumetric component, has a very low heat capacity, whereas a hydrocarbon, like butane, for example, has a relatively high heat capacity. The volumetric heat capacity of butane gas is approximately four times as high as that of hydrogen. The reason for this is the greater weight of butane per unit volume of gas as compared to hydrogen. Recycle gas is a mixture of many gases—its principal component is hydrogen but it also contains substantial quantities of saturated hydrocarbons. Generally, it contains, on a volumetric basis, more methane than ethane, more ethane than propane, more propane than butane, etc. Usually, relatively little C₆ or C₇ hydrocarbons are present.

One way to increase the heat carrying capacity of this recycle gas then is to reduce its hydrogen content and at the same time increase the content of higher molecular weight hydrocarbons, particularly C₄'s, C₅'s, C₆'s, etc. Usually, the hydroformed product is cooled to a temperature of about 100° F. and thereafter the gas and liquid separated. This gas is the product gas and a portion of it is also the recycle gas. The composition of the recycle gas depends upon the quantities of gaseous materials being produced, to some extent on the nature of the liquid product, and very much upon the temperature and pressure of liquid-gas separation. To increase the recycle gas heat carrying capacity, the product may be cooled not to the conventional temperature of about 100° F., but to some higher temperature, say to about 300° F. The following table shows the effect of separator temperature on the specific gravity of the recycle gas and its heat carrying capacity, in a particular case.

Table

Separator Temperature, °F.	100	200	250	300
Recycle Gas, Specific Gravity Relative to Air	0.25	0.36	0.51	0.92
Recycle Gas, Specific Heat, B.t.u./s.c.f. ^{1/2} /°F.	.028	.034	.042	.065
Hydrogen Content, Vol. percent	80	75	71	64

¹ Standard cubic feet.

Thus, by separating at a 300° F. separator temperature instead of 100° F., one can use a recycle gas rate $0.028 \div 0.065 = 42\%$ as great and have the same temperature drop through the reactor system for the same total heat of reaction.

Since the main object of the present invention is to

reduce the hydrogen partial pressure for light naphtha hydroforming by reducing pressure, this reduced hydrogen concentration in the recycle gas actually helps to attain the optimum condition for this light naphtha operation.

It will thus be seen that by means of varying the separator temperature, it is possible to vary the hydrogen partial pressure substantially without any change in the total pressure whatsoever. In actual practice, however, it is preferable not only to increase the separator temperature when lower hydrogen partial pressure is desired, but to reduce pressure at the same time. There are two reasons for this. The first is that thermal cracking reaction is encouraged by the use of higher pressures. Since thermal cracking produces a greater proportion of gas and does not increase the octane number as much as the catalytic hydroforming reaction, the use of higher pressure results in slightly lower yields. Therefore, the combination of reducing pressure and raising separator temperature when running on light feed stocks will give higher yields than the operation where pressure is not decreased but separator temperature is raised sufficiently to give the same hydrogen partial pressure. Another practical reason for preferring the combination of decreasing pressure and raising separator temperature has to do with the recycle gas compressor. Suppose, for example, that one were operating at a pressure such that the suction pressure on the compressor is 350 p.s.i.g. when hydroforming higher boiling feed stocks and using a separator temperature of about 100° F. Now suppose one raises the separator temperature without changing the compressor suction pressure. The change in gas composition increases the horsepower requirement of the compressor so that the compressor and the motor that drives it have to be capable of handling this greater energy requirement. The reason this horsepower requirement increases has to do with the increased density of the recycle gas which it is compressing. While it is quite possible to design the compressor and its driver to handle this higher load, this does increase their cost very substantially. By reducing the suction pressure on the compressor by reducing the overall pressure on the system, one can maintain the horsepower requirement of the compressor essentially constant even while one raises the separator temperature to increase its density.

The manner of operating, outlined above, would result in important economic advantages over a system in which merely the total pressure is decreased during the treatment of the low boiling naphtha constituents because the reheat furnaces and the compressors would be utilized at all times to the full extent of their respective designed capacities.

In the accompanying drawing there is set forth diagrammatically an apparatus layout in which a preferred modification of the present invention may be carried into effect.

Referring in detail to the drawing, naphtha feed is introduced to the present system through line 1. The naphtha is heated in furnace 3 and thence withdrawn in vapor form via line 4 and charged to a separator or fractional distillation column 5, wherein a fraction boiling from 0 to 200° F. is withdrawn overhead through line 6 and charged to a storage drum 7, while a fraction boiling from 200° F. to say 400° F. is withdrawn as bottoms from column 5, line 8 and charged to a heavy naphtha storage drum 9. As will subsequently appear the hydroforming of the naphtha is in a blocked type of operation, that is to say, the heavy naphtha and the light naphtha are separately processed. Toward this end, therefore, while the light naphtha remains in storage in tank 7, the heavy naphtha is withdrawn from tank 9 through valved line 10 and charged to a furnace 11. Simultaneously recycled gas obtained from the product recovery system, as will subsequently appear, is passed via line 12 into line 10 and, therefore, heated in furnace 11 with the

heavy naphtha feed to hydroforming temperatures. This heated mixture is thence withdrawn from furnace 11 through line 13 and charged to the first reactor 14 of a series of reactors. The mixture of heavy naphtha vapors and hydrogen-containing gas passes through reactor 14 in contact with a bed of catalyst C at conditions of temperature and pressure and residence time as hereinafter more fully specified with the result that the naphtha undergoes at least partial hydroforming. Due to the fact that the reaction is highly endothermic there is subsequently a temperature decrease from the inlet to the outlet of reactor 14 so that product withdrawn via line 15 is reheated in the second furnace 16, withdrawn from said furnace and thence passed via line 17 to a second reactor 18 where again the naphtha contacts a bed of catalyst C and undergoes further hydroforming. The product is withdrawn from reactor 18 via line 19 and is reheated in a third furnace 20, withdrawn through line 21 and charged to a third reactor 22 also containing a bed of catalyst and wherein the hydroforming reaction is subsequently completed. The product is withdrawn from reactor 22 through line 23, cooled in 24 to a temperature of about 100° F. thence withdrawn through line 25 and charged to a separation drum 26. From separation drum 26 recycled gas is recovered overhead via line 27, forced through a compressor 28 and charged via line 12 to line 10, as previously explained. Excess recycled gas may be ejected through line 33. The hydroformed product is withdrawn from separator 26 through line 30, passes through valve 37, line 32 and valve 42 to a conventional stabilizing and rerunning system.

In treating the light naphtha under a pressure substantially lower than that maintained during the treatment of the heavy naphtha, the flow of heavy naphtha from storage drum 9 is discontinued and light naphtha is withdrawn from storage drum 7 via valved line 34. It is mixed with recycled gas obtained via line 12 and line 12a and charged to furnace 11 wherein the mixture is heated to reaction temperatures and this mixture is then passed through the series of reactors in the same manner as that previously described in connection with the processing of the heavy naphtha with the exception that, as previously pointed out viz., that the system is now operated at a substantially lower pressure and the separator drum 26 is operated at a substantially higher temperature by controlling the degree of cooling in cooler 24 so that the recycled gas recovered overhead from separator 26 via line 27 is at a substantially higher temperature than that at which the recycled gas exists when processing the heavy naphtha. Product gas for recovery leaves separator 26 through line 29, passes through valve 35 and line 39 to cooler 38. Liquid product passes from the bottom of separator 26 through line 30 through valve 36 and line 40 where it combines with the product gas and passes through cooler 38. Here gas and liquid are cooled to conventional temperatures such as 100° F. and then separated again in vessel 31. Gas product leaves through line 33 and pressure control valve 31 and passes to a conventional gas recovery system. Liquid product leaves separator 31 through line 32 and valve 42, which controls the level in separator 31, and passes to a conventional liquid stabilizing and rerunning system.

The operation described above is completely self-contained. However, it is obvious that the desired increase in recycle gas density and decrease in hydrogen concentration can be augmented by the use of heavy gaseous hydrocarbons such as propane, butane, pentane, etc., from an extraneous source. When this is desired, these gases can be introduced to the recycle gas system through line 43 and valve 44. In the latter case the raw product may be cooled to about 100° F. in 24.

In order to more fully explain the present invention, the following specific example is set forth. A naphtha having the following inspection was processed in the manner set forth immediately below with the results shown.

Inspection:

Boiling range (total naphtha), ° F.	152-387
Naphthenes, vol. percent	43
Paraffins, vol. percent	49
Aromatics, vol. percent	8
Bromine number	0.2
Sulfur, wt. percent	0.005
Octane number, CFRR	55.7

Conditions in reactor 14 during processing of heavy naphtha:

Catalyst composition—	
0.6 wt. percent Pt	
0.6 wt. percent Cl	
98.8 wt. percent eta alumina	
Inlet temperature, ° F.	948
Pressure, p.s.i.g.	420
Residence time, sec.	5.8
Recycle gas feed to reactor, s.c.f./bbl. oil	6000
Density of recycle gas relative to air	0.25
Concentration of H ₂ in recycled gas, mol percent	80
Temperature maintained in separator 26, ° F.	98

In reactor 18 and 22 the catalyst is the same, the pressures are substantially the same (except for the pressure drop involved), the amount of recycled gas in reactor 18 and 22 respectively will be increased somewhat due to the formation of hydrogen and the inlet temperatures of the feed to the reactors 18 and 22 respectively will be substantially the same as the inlet temperature to reactor 14.

Conditions in reactor 14 during processing of light naphtha:

Catalyst composition—	
0.6 wt. percent Pt	
0.6 wt. percent Cl	
98.8 wt. percent eta alumina	
Inlet temperature, ° F.	965
Pressure, p.s.i.g.	256
Residence time, sec.	12.1
Recycle gas feed to reactor, s.c.f./bbl. oil	2280
Density of recycle gas relative to air	0.96
Concentration of H ₂ in recycle gas	62
Temperature maintained in separator 26, ° F.	270

The light and heavy naphtha hydroformates were combined and inspected with the below results.

Inspection:

C ₅ + liquid product yield, vol. percent on feed	83.8
Naphthenes, vol. percent in C ₅ + liquid product	3.5
Paraffins, vol. percent in C ₅ + liquid product	36.9
Aromatics, vol. percent in C ₅ + liquid product	59.6
Bromine number of C ₅ + liquid product	0.08
Sulfur, wt. percent of C ₅ + liquid product	0.0010
Octane number-F-1 of C ₅ + liquid product	96.5

It will be understood that the foregoing example is illustrative of the invention but does not impose any limitation thereof. Good results are obtainable by operating within the following ranges.

Conditions during heavy naphtha hydroforming:

Catalyst—Platinum or palladium suitably supported.	
Inlet temperature, ° F.	900-1000
Pressure, p.s.i.g.	350-600
Residence time, sec.	4-20
Recycle gas feed to reactor, s.c.f./bbl. oil	4000-10,000

Density of recycle gas relative to air	0.1-0.4
Concentration of H ₂ in recycled gas	70-95
Temperature maintained in separator 26, °F.	90-115
Conditions during light naphtha hydroforming:	
Catalyst—Platinum or palladium suitably supported.	
Inlet temperature, °F.	900-1000
Pressure, p.s.i.g.	50-300
Residence time, sec.	8-25
Recycle gas feed to reactor, s.c.f./bbl. oil	1500-3000
Density of recycle gas relative to air	0.40-1.0
Concentration of H ₂ in recycle gas	55-75
Temperature maintained in separator 26, °F	200-325

In order to recapitulate briefly, the present invention contemplates hydroforming a naphtha in the presence of a platinum group metal catalyst disposed in a plurality of reactors in which the naphtha is hydroformed by passage through the said reactors in series under hydroforming conditions of temperature, pressure and contact time. The invention is primarily characterized in that the naphtha is separated into a light boiling fraction and a high boiling fraction and the separated fractions are separately hydroformed. The light naphtha is hydroformed under substantially lower pressure than the heavy naphtha but in order to make full use of the heating and compressor capacity the recycled gas fed to the reaction zone with the low boiling or light naphtha contains a higher percentage of hydrocarbons than does the recycled gas employed in the heavy naphtha. It is thus necessary to so operate the hydroforming of the light naphtha that the recycled gas will contain at least 50% of the heat necessary to support the endothermic reaction of hydroforming. Thus additional hydrocarbons over and above that normally obtained from the product separation drum for recycling is attained by operating the said separation drum at a higher temperature than normally employed and also adding gaseous hydrocarbons either from extraneous sources or from the finishing of the raw hydroformate itself.

Numerous modifications of the invention will be apparent to those who are familiar with this art without departing from the spirit thereof.

What is claimed is:

1. In an adiabatic blocked naphtha hydroforming process carried out in the presence of a platinum group metal catalyst and added hydrogen under hydroforming conditions of temperature, pressure and residence time in a system, the improvement which comprises separating the feed naphtha into a fraction boiling below 200° F. and a second fraction boiling above about 200° F. alternately treating the separated fractions in the same system under hydroforming conditions, characterized in that (1) the lower boiling fraction is treated under a relatively low hydrogen partial pressure, (2) under a lower total pressure and a lower recycle gas rate than said higher boiling fraction, and (3) in which the hydrogen-containing recycle gas fed to the reaction zone during the hydroforming of the said lower boiling fraction possesses a heat capacity substantially greater than the said hydrogen-containing gas fed to the system during the hydroforming of said higher boiling fraction due to the inclusion, in said hydrogen-containing recycle gas fed to the system during hydroforming of the lower boiling fraction of a higher volumetric percentage of hydrocarbons than contained in the hydrogen-containing recycle gas fed to the hydroforming zone during the hydroforming of the said higher boiling naphtha caused by separating the said hydrogen-containing recycle gas from the product obtained by hydroforming the said lower boiling fraction at a temperature of from about 200° to 325° F., whereby increased quantities of aromatics are formed

from paraffins present in the said low boiling naphtha feed, further characterized in that the energy requirements for circulating the said hydrogen-containing recycle gas to the hydroforming treatment of the lower boiling fraction is substantially the same as the energy requirements for circulating recycled gas to the hydroforming treatment of the higher boiling fraction.

2. The method set forth in claim 1 in which extraneous hydrocarbons are admixed with the hydrogen-containing gas fed to the hydroforming zone during the hydroforming of said low boiling naphthas to reduce the hydrogen partial pressure of the said hydrogen-containing gas and at the same time to increase the heat capacity of said hydrogen-containing gas.

3. An improved process for hydroforming a naphtha containing both high and low boiling naphtha fractions in a system comprising a plurality of reactors, each containing a platinum group metal catalyst characterized in that the naphtha is passed in series, together with a hydrogen-containing recycle gas, through the several reactors

in contact with the said catalyst, the improvement resulting in producing a hydroformed product of improved octane rating in increased yield due at least in part to an increased yield of aromatics formed from paraffinic hydrocarbons in the said low boiling fractions which comprises separating the naphtha into a low boiling fraction and a high boiling fraction, separately hydroforming the said fractions in the said system at elevated temperatures and under elevated pressures, the said fraction

containing the low boiling naphtha fractions being hydroformed under a hydrogen partial pressure lower than that existing during the hydroforming of the high boiling naphtha fractions, further characterized in that the rate at which the hydrogen-containing gas is fed to the system

during the low boiling naphtha treatment is substantially less than when the high boiling fractions are undergoing treatment, recovering raw products from the respective treatments, cooling the raw products to condense normally liquid constituents, recovering a hydrogen-containing gas from both treatments for recycle to the process

and causing an increase in the heat carrying capacity of the hydrogen-containing recycle gas for use during the treatment of the low boiling hydrocarbon fractions by separating the said hydrogen-containing gas from the low boiling hydroformed liquid product at a temperature of from about 200°-300° F., further characterized in that the energy requirements for circulating the said hydrogen-containing recycle gas to the hydroforming treatment of the lower boiling fraction is substantially the same as the energy requirements for circulating recycled gas to the hydroforming treatment of the higher boiling fraction.

4. The method set forth in claim 1 in which the energy requirements for recycling the hydrogen-containing gas is maintained substantially constant for both treatments by hydroforming the light hydrocarbon fractions under a total pressure substantially lower than that existing in the reaction zones during the hydroforming of the higher boiling naphtha fractions.

5. The method set forth in claim 3 in which the hydroforming is carried out in the presence of a catalyst containing platinum.

6. The method set forth in claim 3 in which the said low boiling naphthas comprise a fraction boiling in the range of from about 0°-200° F.

7. The method set forth in claim 4 in which the pressure maintained during the hydroforming of the lower boiling hydrocarbon fractions is from about 50 to 300 p.s.i.g.
